MATCH-BOX.

1,168,670

specification of Letters Patent. Patented Jan. 18, 1916.

Application filed December 17, 1914. Serial No. 277,750.

To all whom it may concern:

Be it known that we, STEVE PEERSE and ROBERT MAUSSER, subjects of the Emperor of Germany, residing at East Helena, in the county of Lewis and Clark and State of Montana, have invented certain new and useful Improvements in Match-Boxes, of which the following is a specification, reference being had therein to the accompanying drawing.

This invention relates to match boxes and has for its object to provide a device of such class, in a manner as hereinafter set forth, with a spring controlled storage receptacle for the matches and to further provide means associated with the receptacle for detachably securing the latter within the inclosing casing.

Further objects of the invention are to provide a match box which is comparatively simple in its construction and arrangement, strong, durable, efficient and convenient in its use, readily set up and comparatively inexpensive.

With the foregoing and other objects in view the invention consists of the novel construction and arrangement of parts as hereinafter more specifically described and illustrated in the accompanying drawings where-
30 in is shown an embodiment of the invention, but it is to be understood that changes, variations and modifications can be resorted to which come within the scope of the claims hereunto appended.

35 In the drawings wherein like reference characters denote corresponding parts throughout the several views: Figure 1 is a cross sectional view of a match box in accordance with this invention. Fig. 2 is a side elevation. Fig. 3 is a longitudinal section. Fig. 4 is an end view.

Referring to the drawings in detail 1 denotes a rectangular casing, which is open at one end as shown at 20, and closed at its other end as shown at 21 and arranged within the casing 1 is a spring controlled receptacle 2. The casing 1 is capable of being projected through the open end 20 of the casing 1. The outer end of the receptacle 2 is serrated as shown at 3 to provide a striking surface for a match. The matches are adapted to be retained within the receptacle 2. Connected to the inner face of the closed end 21 of the casing 1, is a lug 4, and surrounding the latter, as well as bearing against the inner end of the receptacle 2, is

a coil spring 5, the function of which is to project the receptacle 2 from the casing 1. A cover 6 is provided, which incloses the sides and top of the casing 1, as well as being spaced from said sides and top, and said cover 6 is secured to the casing 1, as at 7.

The side walls of the receptacle 2, have openings 8 which are adapted to register with openings 9 formed in the side walls of the casing 1. Extending in the openings 8, and capable of extending into the openings 9, are the lower ends of pivoted locking members 10, these latter being pivoted as at 11, to lugs 12, carried by the casing 1. The locking members 11 extend at the sides of the casing 1 and also over the top thereof and have interposed there-between and the top of the casing 1, coil springs 13 which normally tend to maintain the lower ends of the locking members 10 in the registering openings 8, 9, under such conditions maintaining the receptacle 2 within the casing 1, against the action of the spring 5. The top of the casing 1 has a vertically disposed pin 14 and surrounding said pin is a coil spring 15.

The reference character 16 denotes a push button accessible through an opening 25 in the cover 6. The button slides upon the pin 15 and is adapted to have its head engage the inner ends of the members 10, under such conditions rocking said members on their pivots and shifting the lower ends of the members 10 out of the openings 8 and allowing the spring 5 to force the receptacle 2 from the casing 1, so that access can be had to the matches stored within the receptacle. When the spring 15 raises the button 16, the cover 6 acts as an abutment for the button, so that the latter is not disengaged from the pin 14.

What we claim is:

1. In a device of the class described, a casing; a receptacle slidable within the casing; spring means for advancing the receptacle; a cover secured to the casing and spaced from the top and the sides of the casing, the cover having an opening; a pair of levers fulcrumed intermediate their ends on the casing and located within the cover, the inner ends of the levers lying above the top of the casing and the outer ends of the levers extending along the sides of the casing, the casing and the receptacle being provided with openings in which the outer ends of the levers are received to hold the

receptacle within the casing; a pin projecting from the casing; a push button slidable on the pin and adapted to engage the inner ends of the levers, the push button being located in alignment with the opening in the cover; a spring surrounding the pin and abutting against the button and the casing; and spring means for tilting the levers to cause the outer ends thereof to engage in the openings in the casing and the receptacle.

2. In a device of the class described, a casing; a receptacle slidable in the casing; spring means for advancing the receptacle; a cover secured to the casing and spaced from the top and the sides of the casing, the cover having an opening; a lever fulcrumed intermediate its ends on the casing, the inner end of the lever lying above the top of the casing and the outer end of the lever lying along the side of the casing, the casing and the receptacle being provided with openings in which the inner end of the lever engages; a push button slidably supported below the opening in the cover and engaging the inner end of the lever; and spring means for holding the outer end of the lever in the openings in the casing and the receptacle.

3. In a device of the class described, a casing; a receptacle slidable in the casing; a cover secured to the casing and spaced from the top and the sides of the casing, the cover having an opening in its top; a pair of oppositely disposed casing-carried locking members engaged at their outer ends with the sides of the casing and the receptacle.

ceptacle; and means housed beneath the cover and accessible through the opening therein for actuating both locking members at once to effect a release of the locking members from the receptacle. 40

4. In a device of the class described, a casing; a receptacle slidable in the casing; spring means for advancing the receptacle; a cover secured to the casing and spaced from the top and the sides of the casing, the cover having an opening in its top; and a lever fulcrumed intermediate its ends on the casing, the inner end of the lever extending beneath the cover and above the top of the casing and below the opening, the outer end of the lever being extended along the side of the casing and being detachably interengaged with the casing and the receptacle. 45

5. In a device of the class described, a casing; a cover assembled therewith; a receptacle slidable in the casing; spring means for advancing the receptacle; two opposed movable locking devices within the cover and engaging the receptacle at opposed points; and a single movable means housed within the cover for actuating both locking devices at once to effect a release of the receptacle. 50

In testimony whereof we affix our signatures in the presence of two witnesses.

STEVE PERSE.
ROBERT MAUSSER.
